(57) **CLAIM**

The ornamental design for a portion of a display panel with animated graphical user interface, as shown and described.

DESCRIPTION

The file of this patent contains at least one drawing executed in color. Copies of this patent with color drawings will be provided by the Office upon request and payment of the necessary fee.

FIG. 1 is a front view of a portion of a display panel with a first animated graphical image, showing the claimed design.

FIG. 2 is a second image thereof.

FIG. 3 is a third image thereof.

FIG. 4 is a fourth image thereof.

FIG. 5 is a fifth image thereof.

FIG. 6 is a sixth image thereof.

FIG. 7 is a seventh image thereof.

FIG. 8 is an eight image thereof; and,

FIG. 9 is a ninth image thereof.

The subject matter in this patent includes a process or period in which an image changes into another image. This process or period forms no part of the claimed design.

The broken lines showing a portion of a display panel form no part of the claimed design.
